UNITED STATES PATENT OFFICE.

JOHAN SHEEVER, OF MINEVILLE, NEW YORK.

DESIGN FOR AN ANVIL.

60,064.

Specification for Design.

Patented Dec. 20, 1921.

Application filed February 28, 1921. Serial No. 448,610. Term of patent 14 years.

To all whom it may concern:

Be it known that I, JOHAN SHEEVER, a citizen of the United States, residing at Mineville, in the county of Essex and State of New York, have invented a new, original, and ornamental Design for an Anvil, of which the following is a specification, reference being had to the accompanying drawings, forming a part hereof.

The figure is a perspective view showing my new design for an anvil.

I claim:

The ornamental design for an anvil, as shown.

JOHAN SHEEVER.
